1

This invention relates generally to devices for generating ultra-high frequency electrical oscillations, i. e. in the centimeter range, and more particularly to those of the type in which electrons emitted radially from an elongated cathode transfer energy to an annular hollow resonator arranged concentric about the axis of the cathode. The resonator has annular end walls bounded in a radial direction by outer and inner cylindrical walls, and the inner wall is constituted by a cylindrical array of spaced anode segments, adjacent segments in the array being secured to opposite end walls such that alternating potentials are developed between adjacently positioned segments as the resonator oscillates. Through the combined actions of a constant radial electric field established between the cathode and the array of anode segments by an applied potential and a unidirectional magnetic field established axially, the electrons leaving the cathode are caused to travel in cycloidal paths and form into bundles which then give up energy, originating from the constant electric field to the alternating field of the cavity resonator to maintain the latter in a state of oscillation at a constant frequency which is determined solely by its dimensions and the capacity between the anode segments. The appearance of this type of generator which is described in further detail in my co-pending United States application, Ser. No. 478,533, filed March 9, 1943, and also in an article prepared by me which appeared in *Helv. Phys. Acta*, vol. XIII Fasc. Sext. (1940), is somewhat like that of an alternating current machine. The cavity resonator determining the frequency along with the anode segments resembles a stator while the motion of the electron bundles corresponds to the movement of the rotor.

While this type of micro-wave generator has been found to produce generally satisfactory results, it does, however, have one operating disadvantage that stems from the so far unavoidable coupling between the high frequency magnetic field within the resonator and the cathode which it encloses.

Such coupling causes a loss of energy because of the high frequency currents induced in the cathode that are free to flow off on the cathode input line, and makes it possible, through the coupling, for the high frequency field to be disturbed by extraneous fields and charges that under optimum operating conditions should be entirely excluded.

The general object of the present invention

2

is to overcome the above mentioned undesirable operating characteristic by eliminating the coupling between the high frequency magnetic field of the cavity and the cathode and specifically by providing at least two cavity resonators enclosing the cathode and coupling these resonators in a manner such that the instantaneous sum of the high frequency fields simultaneously affecting the cathode is always equal to zero. 10 By so doing, the undesirable high frequency currents are no longer induced in the cathode line, the resonators are completely isolated from all harmful extraneous effects and one also is able to enjoy the additional advantage of a much 15 broader latitude in designing the cathode structure per se since research has shown that large surfaced cathodes are desirable in the interest of increasing the efficiency of the generator, the ratio of the anode to the cathode diameters 20 being particularly important.

Another specific object is to provide an improved micro-wave generator having a pair of intercoupled cavity resonators, the high frequency fields of which are displaced 180° apart in phase.

Yet another specific object is to provide an improved micro-wave generator having three associated cavity resonators for use in producing three phase oscillations, the high frequency oscillations of the several phases being intercoupled so as to be displaced 120° apart in phase.

The foregoing as well as other objects and advantages that stem from the present inventive concept will become more apparent from the

30 following detailed description of several practical constructions for micro-wave generators incorporating the invention when considered with the accompanying drawings. Fig. 1 is a perspective view illustrating one embodiment of the invention in which the generator is provided with a pair of adjacent interconnected cavity resonators, the oscillations of which are spaced 180° apart in phase; the usual magnetic structure by which a unidirectional magnetic field is established 35 parallel to the axis of the cathode has been omitted for the sake of simplicity. Fig. 2 is a vertical section taken along the axis of the cathode of a slightly different construction for a dual resonator generator, the pole pieces of the 40 associated magnetic structure being also included. Fig. 3 is a view in perspective of the dual cavity resonator shown in Fig. 2. Fig. 4 is a schematic diagram illustrating the type of 45 high frequency oscillatory circuit produced by 50 the generators illustrated in Figs. 1 and 2. Fig. 55

5 is a vertical section of a dual cavity resonator structure illustrating a modified arrangement for interconnecting the two resonators. Fig. 6 is a vertical section of still another structural arrangement for the plurality of interconnected cavity resonators, this form providing three resonators, the oscillations of which are spaced 120° apart in phase. And Fig. 7 is a view similar to Fig. 1 illustrating a modified arrangement for leading the resonator and cathode conductors through the envelope surrounding the generator elements.

Referring now to Fig. 1, the improved high frequency generator is seen to include the usual cathode 1, heated indirectly by filament 1a, having a relatively large surface for the emission of electrons and which lies along the axis of a pair of annular, adjacently positioned, cavity type resonators legended A and B. The two resonators are combined in a single hollow cylindrical conductive structure made up from an outer cylindrical wall 3 of conductive material extending longitudinally of the cathode, annular conductive end walls 4 and 5 extending transversely of the cathode, a third transverse annular conductive wall 6 placed intermediate the end walls 4, 5, and an inner cylindrical wall parallel with the outer wall 3. This inner wall is comprised of a cylindrical array of spaced anode segments 7 extending parallel to the cathode inwardly from end wall 4 to a point just short of intermediate wall 6, a similar array of anode segments 8 extending inwardly from end wall 5 and which are aligned with the anode segments 7, and a third cylindrical array of spaced anode segments 9, 10 carried by the intermediate wall 6 and which extend respectively in opposite directions therefrom. Anode segments 9, 10 likewise lie parallel to the cathode axis in the spaces between anode segments 7, 8 and terminate just short of the end walls 4, 5.

Resonator A is thus constituted by the cavity defined by outer wall 3, anode segments 7, 9 and transverse walls 4, 6; and resonator B is constituted by the cavity defined by outer wall 3, anode segments 8, 10 and transverse walls 5, 6.

The capacity component of each resonator consists principally of the inter-leaved segments carried by the end and intermediate walls, respectively and these segments during operation are at any instant of opposite polarity. Thus for example in resonator A, at the instant that the anode segments 7 secured to end wall 4 are charged positive, the anode segments 9 secured to intermediate wall 6 will be charged negative, and vice versa, as the resonator circuit oscillates.

Resonators A and B and the cathode 1 are all enclosed within an evacuated envelope 11; a post 12 beaded into the lower end of the envelope is used to support the resonator structure; filament 1a and the surrounding cathode 1 are anchored in place by rigid lead-in conductors 13, 14 for the filament current which are also beaded into the lower end of the envelope; and parallel arranged lead-off conductors 15, 16, 17 for the high frequency oscillations produced by the generator extend through bead type seals at the upper end of envelope 11 in a direction perpendicular to the cathode axis, it being noted that conductor 16 is connected directly to the outer wall 3 at the common intermediate wall 6 separating the two resonators A and B while conductors 15 and 17 pass through slots 18, 19 in outer wall 3 well into the interior of the resonators A and B, respectively, and there are turned through 90° so

as to present short, co-axially aligned coupling i. e. energy extracting sections 15a, 17a extending towards each other in a direction parallel to the cathode axis and which terminate at the intermediate wall 6 and are electrically connected to the latter at the junction point.

The construction of the ultra-high frequency generator shown in Figs. 2 and 3 is substantially the same as the one shown in Fig. 1 and for ready comparison between the two structures, like reference numerals but with primes added thereto have been used to designate like parts in the two structures. In addition, the pole pieces 22, 23 of a generally C-shaped magnet are shown in Fig. 2 at opposite ends of the cathode 1' on which are wound field coils 24, 25 that are energized from a source of direct current, not illustrated, to establish a unidirectional magnetic flux parallel to the cathode axis which is essential to the generator. As previously explained, the corresponding field structure associated with Fig. 1 has been omitted in the interest of simplifying the disclosure.

As can be readily observed by a comparison of Figs. 1 and 3, the only difference between the generator constructions in Figs. 1 and 2 lies in the manner in which the anode segments associated with the end walls of the resonators are arranged. In Fig. 1, two galvanically separate and aligned arrays of segments 7 and 8 are utilized whereas in Fig. 3, the aligned segments in each array are seen to be continuous between the two end walls 4', 5', and arcuate notches 26 are cut into the intermediate plate 6' to prevent contact between the latter and these segments. Thus although the anode segments are actually one continuous body of material, separate legends 7', 8' have nevertheless been used thereon to designate the anode portions associated respectively with resonators A' and B'.

It will now be apparent from what has been said that the generators shown respectively in Fig. 1, and Figs. 2, 3 each provide dual, high frequency oscillatory circuits, one including resonator A and the other resonator B, with the cathode 1 common to both circuits. Considered separately, each of the resonators operates in accordance with the previously explained principles.

As stated at the outset, the principal object of this invention is to more effectively isolate the cavity resonator component of the generator from all extraneous charges or fields that might exert a disturbing influence on the high frequency oscillations generated because of the inductive coupling between the high frequency magnetic field and cathode. The desired result is obtained in Fig. 1 and Figs. 2, 3 by providing dual resonators and arranging these such that the respective phases of the high frequency fields are staggered by 180°. That is to say, the field in one resonator is always opposite in direction to that in the other resonator, such condition being illustrated schematically in Fig. 2 by the usual $\oplus$ and $\ominus$ direction symbols. Under these conditions, the induction effects of the two high frequency fields nullify each other with respect to the cathode, thereby eliminating the generation of high frequency currents in the latter which heretofore had been the cause of the operating difficulties.

The necessary opposite-phase condition can be produced by establishing a coupling between the adjacent resonators of the generator. For a better understanding of the nature of the coupling

to be applied, reference should be made to Fig. 4 that shows schematically two oscillatory circuits *a* and *b* connected in parallel and oscillating in opposite phase as indicated by the directional arrows. Oscillatory circuit *a* corresponds to resonator A and oscillatory circuit *b* to resonator B. Condenser plates 30 of circuit *a* represent the capacitance of anode segments 7, 9 of resonator A; condenser plates 31 of circuit *b* represent the capacitance of anode segments 8, 10 of resonator B; coil 32 represents the inductance of circuit *a* constituted by end walls 4, 6 and that half of outer wall 3 included therebetween; and coil 33 the inductance of circuit *b* constituted by end walls 5, 6 and the other half of outer wall 3 included therebetween.

The coupling between points 34 and 35 of the two circuits in the generator shown in Fig. 1, and also in the modified construction shown in Figs. 2, 3 is established by the conductive intermediate wall 6 which is common to both resonators. The coupling between points 36 and 37 of the two oscillatory circuits is, however, established by different means in the two constructions; in Fig. 1, such coupling is produced by direct connection of the symmetrically arranged coupling loops 15a, 17a of the two lead-off conductors 15, 17 which terminate at the conductive intermediate wall 6; while in the Fig. 2 construction, such coupling is established by virtue of the fact that correspondingly positioned anode segments 7, 8' of the two resonators A, B are constituted by a continuous body of conductive material extending between the end walls 4' and 5'.

Fig. 5 illustrates still a third manner of forming the connection between points 36, 37 of the two oscillatory circuits *a* and *b* for a generator having the resonator structure of Fig. 1. Here it is seen that the necessary interconnection is established by a conductor 38 having a coupling loop 38a disposed within resonator A'' and a similar coupling loop 38 within resonator B'' but looped in the opposite direction, the terminal ends of the conductor being connected to the intermediate transverse wall 6'', and being passed through an opening 39 in the latter.

It is easily seen that only a state of oscillation can be formed which induces like-directed currents in the two looped portions of conductor 38, as shown by the direction arrows. This is possible, however, only when the two fields are in opposite phase, as shown, the purpose of the wire loop 38 being thus filled.

Fig. 6 illustrates in a somewhat diagrammatic form a further modification utilizing three resonators intercoupled in such manner that their respective high frequency fields are staggered in phase by 120 electrical degrees. This form of generator is especially suited for producing three phase high frequency oscillations. Basically, this form of the invention is the same as that shown in Fig. 1 and, in the interest of simplifying the drawings, only those anode segments lying in the plane of the cathode axis *x*—*x* have been illustrated, and the cathode itself has also been excluded. As with the other embodiments, the resonator structure is comprised of an outer cylindrical wall 40, parallel with the cathode axis, annular end walls 41, 42 transverse to the cathode axis and a pair of annular transverse walls 43, 44 intermediate the end walls so located as to divide the interior into three, like dimensioned resonators C, D and E. Circular arrays of anode segments 45, 46 extend inwardly from end walls 41, 42 respectively, and circular arrays of anode seg-

ments 47, 48 extend in both directions from the intermediate walls 43, 44, respectively, so as to lie in the spaces between the anode segments 45, 46.

5 Coupling loops 51, 52 and 53 extend respectively into the three resonators C, D and E for extracting high frequency energy from the generator, and these lead via concentric lead-off wave guides 54, 55, 56 to a star connected three phase load apparatus indicated diagrammatically by the rectangles 57.

In order that the three resonators C, D and E shall have the necessary phase displacement of 120°, coupling connections 58, 59 must be provided. Connections 58, seen to be of the capacity type couples conductors 54 and 55; and connection 59, also of the capacity type couples conductors 54 and 56. By correct choice of the distance *y* and *z* between the outer wall 40 and 15 coupling connection 58, 59 respectively, which in the simplest manner is determined empirically, the desired phase displacement between resonators C, D, E can be effected without difficulty, so that, for example, resonator D oscillates with 20 a phase displacement of 120° in relation to resonator C, and resonator E with a phase displacement of 240° in relation to resonator C. In this way, the sum of the inducing effects of the high frequency magnetic fields of all three resonators 25 on the cathode is equal to zero, and radiation of high frequency energy through the cathode made impossible.

In the dual resonator generator construction shown in Fig. 1, it is of advantage to make the 30 connection between the high frequency conductors inside of the envelope so that only two conductors need be carried out of the envelope for coupling out the high frequency energy. Such an arrangement is illustrated in Fig. 7 where it 35 will be seen that lead-off conductor 15'' is connected by a bridge 60 to conductor 17'' within the envelope 11'', and hence only conductors 17'' and 16'' are then necessary for leading 40 out the high frequency energy. The two cathode lead-ins 13'', 14'' are then preferably led out 45 of the envelope 11'' on the same side as conductors 16'', 17'', the four conductors being arranged in the form of a cross.

I claim:

- 50 1. A micro-wave generator comprising a cathode; a plurality of like annular hollow resonators surrounding said cathode and located in side-by-side relation along the cathode axis and concentric therewith, each of said resonators 55 including annular end walls and bounded in a radial direction by an outer cylindrical wall and an inner wall constituted by a cylindrical array of interfitting anode segments terminating in alternation on said end walls; means adjacent 60 said resonators for establishing a unidirectional magnetic field within the space defined by said inner wall of each resonator and parallel to the common axis thereof; means symmetrically arranged in the respective resonators for extracting high frequency energy therefrom; and means intercoupling said resonators together and so constructed and arranged that the inductive effect of the high frequency magnetic fields produced respectively by the resonators 65 with respect to the cathode is zero.
- 70 2. A micro-wave generator as defined in claim 1, wherein said means intercoupling said resonators includes said symmetrically arranged means for extracting high frequency energy from 75 the respective resonators.

3. A micro-wave generator comprising an evacuated envelope housing a cathode; an annular resonator structure disposed concentrically about said cathode, said resonator structure comprising annular end walls, an outer cylindrical wall extending between said end walls, an intermediate annular wall parallel with said end walls and an inner cylindrical wall constituted by a cylindrical array of interfitting anode segments terminating in alternation on said end and intermediate walls, the annular space defined between one of said end and intermediate walls and the inner and outer wall section therebetween constituting one resonator, and the similar space defined by said intermediate wall and the other end wall and by the sections of the inner and outer walls therebetween constituting a second resonator; means adjacent said resonators for establishing a unidirectional magnetic field within the space defined by the inner wall of each resonator and parallel to the common axis thereof; lead-off means coupled to each resonator for extracting high frequency energy therefrom; and means including said intermediate wall that is common to both resonators coupling the latter together in parallel and so constructed and arranged that the inductive effect of the high frequency magnetic fields produced respectively by the resonators with respect to said cathode is zero.

4. A micro-wave generator as defined in claim 3 wherein said coupling means comprises means coupling together the high frequency lead-off means of the respective resonators.

5. A micro-wave generator as defined in claim 3 wherein said coupling means comprises means interconnecting the high frequency lead-off means for each resonator within the envelope enclosing said generator, and said lead-off means together with the input leads to said cathode are disposed in the form of a cross at their sealed pass-through points in the envelope.

6. A micro-wave generator as defined in claim 3 wherein said coupling means comprises a coupling loop extending through an aperture in said intermediate wall into both resonators and which surrounds the respective high frequency fields of the resonators in inverse sense.

7. A micro-wave generator comprising a cathode; three annular hollow resonators disposed concentrically about said cathode in side-by-side relation, each of said resonators including annular end walls and bounded in a radial direction by an outer cylindrical wall and an inner wall constituted by a cylindrical array of interfitting anode segments terminating in alternation on said end walls; means adjacent said resonators for establishing a unidirectional magnetic field within the space defined by the said

inner wall of each resonator and parallel to the common axis thereof; lead-off means symmetrically positioned with respect to the respective resonator for extracting high frequency energy therefrom; and means intercoupling said resonators together and so constructed and arranged that the respective high frequency magnetic fields produced by said resonators are 120° apart in phase.

10 8. A micro-wave generator as defined in claim 7 wherein said intercoupling means includes capacity type connections extending between said lead-off means.

15 9. A micro-wave generator comprising a cathode; an annular hollow resonator structure disposed concentrically about said cathode, said resonator structure comprising end walls, an outer cylindrical wall connecting said end walls, a pair of spaced annular walls arranged parallel with said end walls and intermediate thereof, and an inner wall constituted by a cylindrical array of interfitting anode segments terminating in alternation on said end and intermediate walls, the annular spaces defined respectively between said end and intermediate walls and the inner and outer wall sections therebetween constituting three like resonators; means adjacent said resonator structure for establishing a unidirectional magnetic field within the space defined by the inner wall of each resonator and parallel to the common axis thereof; lead-off means cooperative with each resonator for extracting high frequency energy; and means including said intermediate walls intercoupling said resonator chambers together and so constructed and arranged that the inductive effect of the high frequency magnetic fields produced respectively by the resonators with respect to said cathode is zero.

20 40 10. A micro-wave generator as defined in claim 9 wherein the means intercoupling said resonators also includes capacitive type connections between the said lead-off means cooperative with the several resonators.
